UNITED STATES PATENT OFFICE.

OLAF JOHAN SWANSON, OF CHAPPAQUA, NEW YORK.

FLY-PAPER HOLDER.

Application filed October 22, 1921. Serial No. 509,538.

To all whom it may concern:

Be it known that OLAF JOHAN SWANSON, a citizen of the United States of America, residing at Chappaqua, in the county of West-
5 chester and State of New York, has invented new and useful Improvements in Fly-Paper Holders, of which the following is a specification.

The object of the invention is to provide
10 a simple and efficient means for holding
sticky fly paper of the Tanglefoot type
usually provided in sheets, and more par-
ticularly to provide a means for containing
such sheets under conditions permitting ac-
15 cess of flies and other insects to the sticky
surface thereof while protecting the same
from other objects and guarding against the
sticky surface coming in contact with sur-
rounding objects especially when exposed to
20 a draft; and with this object in view the
invention consists in a construction and com-
bination of parts of which a preferred em-
bodiment is shown in the accompanying
drawings, wherein:—
25 Figure 1 is a perspective view of a holder
embodying the invention.

Figure 2 is a plan view of the blanks
constituting the tray and its end gate or
closure.

30 Figures 3 and 4 are detail views of the
blank from which the handle and one of
the guard strips are formed.

Figure 5 is a perspective view of a hanger
by which the device may be supported from
35 a shelf or ceiling.

The device consists essentially of a tray 10
having upturned side and end edges forming
walls or flanges 11, one end of the tray
preferably being formed separately from the
40 body portion of the tray to provide an end
gate or closure 12 also flanged as shown at
13 and adapted to be fitted over the open
end of the body portion of the tray after
45 placing a sheet of sticky fly paper in the
former as a means of locking the sheet in
place against endwise movement and facil-
itating the introduction of said sheet. A slip
connection is provided between the end gate
50 or closure and the body of the tray.

In the side walls or flanges of the tray

are formed notches 14 with intermediate fin-
gers 15 for engagement with openings 16 in
a strap 17 which constitutes a handle or belt
by which the tray may be carried and which
also serves as a guard to prevent objects
55 from dropping or being accidentally placed
in the tray where they will be subject to con-
tact with the surface of the fly paper. As
a further means of protecting the surface
of the fly paper transverse guard bars 18
60 may be arranged to connect the side walls
of the tray at opposite sides of the plane
of the arched guard or handle 17.

To provide for supporting the holder in
a pendent position one extremity of the han-
dle member 17 may be folded outward paral-
lel with the bottom of the tray to form an
ear 19 and provided with an opening 20 for
engagement with the nail or hook.

The device is of such construction as to be
70 formed from a sheet of material either card-
board, metal or any equivalent thereof, and
is also of such a construction as to adapt it
to be packed and shipped in a flat condi-
tion and folded into proper form when re-
quired for use. If the device is for example
75 of cardboard the attachment of the ends
of the walls and of the extremities of the
bars with the walls may be effected by any
suitable adhesive material such as mucilage
80 or the like, and thus provision is made for
packing the holder with the sheets of fly
paper so that the holder may be set up by
the consumer who purchases the fly paper.

In Figure 5 there is shown a modification
of the invention consisting of a hanger
made of two strands of wire twisted to pro-
vide a shank as shown at 21 and a terminal
eye 22, the divergent arms 23 being inturned
85 at their lower extremities as indicated at 24
and provided with hooks on which the bot-
tom of the tray may rest.

Having described the invention, what is
claimed as new and useful is:—

1. A fly paper holder consisting of a tray
90 having side and end walls or flanges and
transverse guards connecting the side walls,
one of said guards arranged at an interme-
diate portion of the length of the tray being
95 arched to form a handle and being provided
100

near its extremities with openings for engagement by tongues formed on the side walls of the tray.

2. A fly paper holder consisting of a tray having side and end walls or flanges and transverse guards connecting the side walls, one of said guards arranged at an interme-

diate portion of the length of the tray being arched to form a handle and having a terminal perforated eye for supporting the tray 10 in a pendent position.

In testimony whereof he affixes his signature.

OLAF JOHAN SWANSON.
